UNITED STATES PATENT OFFICE.

FRED L. STONE, OF SCHENECTADY, NEW YORK, ASSIGNOR TO GENERAL ELECTRIC COMPANY, A CORPORATION OF NEW YORK.

SPEED-LIMITING DEVICE.

No. 849,753.

Specification of Letters Patent.

Patented April 9, 1907.

Application filed September 21, 1903. Serial No. 173,981.

To all whom it may concern:

Be it known that I, FRED L. STONE, a subject of the King of Great Britain, residing at Schenectady, in the county of Schenectady and State of New York, have invented certain new and useful Improvements in Speed-Limiting Devices, of which the following is a specification.

The present invention relates to speed-limiting devices, and more particularly to that class of speed-limiting devices which operate through the making or breaking of an electric circuit to actuate power regulating or controlling mechanism.

My invention has for its object to provide a device of this character which is adapted to be applied with facility to complete machines of various types non-cloggable by grease and dirt, positive and sensitive in action, and of low cost of manufacture.

In the accompanying drawings, forming a part of this specification, I have shown a particular embodiment of my invention.

Figure 1 is a vertical longitudinal section of a speed-limiting device shown in connection with a shaft and bearing of an ordinary electric motor. Fig. 2 is a side elevation of the same. Fig. 3 is a transverse section on the line 3-3 of Fig. 2, and Fig. 4 is a left-hand elevation of the stationary contacts and their support.

The stationary contacts 1 and 2 are connected in practice through the lead-wires 3 and 4 to suitable translating devices, (not shown,) by which the power applied to the rotary machine is controlled or regulated.

The movable contact 5, by which the electric circuit is automatically completed between the stationary contacts 1 and 2, is carried by a spring-pressed plunger 6, normally held in retracted position by latch means mounted to rotate with the rotary part A of the machine and adapted to operate under centrifugal force to release the plunger when a predetermined speed is exceeded.

The contact 5 consists of a flat metallic disk and is secured to the plunger 6 by means of screws 7 and 8, extending through an intervening plate of insulation 9. The body part of the plunger 6 consists of a metallic cylinder having a peripheral notch or groove 10, a longitudinal side slot 11, and an axial cavity 12, into which extends a sup-

porting stub-shaft 13, upon which the plunger is free to move longitudinally.

The stub-shaft 13 is provided on one side with a guide-pin 14, which extends into the side slot 11 of the plunger to prevent relative rotation of these parts, so that the plunger 6 is caused to rotate with the rotary part A of the machine, and when released the contact-plate 5 is caused to rub upon the stationary contacts 1 and 2, removing thereby all adhering particles of foreign matter and insuring perfect electrical contact. The center of the shaft 13 is cored out for the reception of the plunger-actuating spring 15 and its guide-pin 16, and the inner end of the shaft is connected to a circular attaching-plate 17.

The attaching-plate 17 is provided with two posts 18 and 19 and countersunk holes 20 for the screws, whereby it may be connected to the end of a shaft or other rotary element. Post 18 is made cylindrically and is provided with a reduced outer end 21, upon which are pivoted a latch-lever 22 and a weighted lever 23, which are held thereon by a nut 24, engaging the outer threaded end of the reduced portion 21. The latch-lever 22 has one arm 25 bent inwardly to enter the peripheral groove 10 in the plunger, and the other arm 25' is extended beyond the plunger on the opposite side thereof from the end 25, and a helical spring 26, surrounding the cylindrical post 18, engages at its end with the attaching-plate 17 and the lever 22 and operates to hold the bent end 25 of the lever pressed toward the plunger.

The weighted lever 23 is made with one end much heavier than the other, so that as it revolves the heavier end will tend to move outwardly under centrifugal force. The lighter end 27 is offset into the path of arm 25' of the latch-lever, so that when the weighted end moves outwardly the latch-lever will be engaged and forced out of the path of the plunger 6. The means for holding the weighted lever in its inner position and for regulating the force exerted thereon consists of a helical spring 28, secured to a projection 29 from the back of the lever and to a screw-eye 30, extending through the post 19 and engaged by a thumb-nut 31.

The stationary contacts 1 and 2 comprise segmental strips of spring metal provided with binding-screws 32 and are secured to a

plate of insulation 33, held by screws 34 to one side of a support 35, having a parallel-sided arm 36, extending through and adjustably secured in an aperture of a bracket 37, bolted 5 to the bearing-block or other stationary part B of the machine.

The means for returning the plunger 6 to its retracted position consists of a push-rod 38, extending through the support 35 in line 10 with the axis of the plunger and provided at its inner end with a flat head 39 and at its outer end with a button 40. The support 35 is cored out at 41 for the reception of a helical retracting-spring 42 and the end of the button 40.

It is to be noted in the construction herein described that there are but two parts—the plate 17 and the bracket 37—requiring attachment in order to connect the device to any 20 ordinary shaft and its bearing, that the construction of parts is such that exact centering is unnecessary, and that the action of the several parts is positive.

I do not desire to restrict myself to the particular construction or arrangement of parts shown and described herein, since it is apparent that they may be changed and modified without departing from my invention.

What I claim as new, and desire to secure 30 by Letters Patent of the United States, is—

1. In a speed-limiting device for rotary machines, the combination of a stationary contact, a spring-pressed movable contact mounted to rotate with the machine, and 35 latch means controlled by centrifugal action for holding said movable contact in retracted position and automatically releasing it upon a predetermined speed being exceeded.

2. In a speed-limiting device for rotary 40 machines, the combination of a stationary contact, a spring-pressed axially-moveable contact mounted to rotate with the machine, and latch means controlled by centrifugal action for holding said movable contact in retracted position and automatically releasing it upon a predetermined speed being exceeded.

3. In a speed-limiting device for rotary 45 machines, the combination of a stationary contact, a spring-pressed axially-moveable contact, a support for said movable contact having a feathered connection therewith and adapted to be operatively connected with the rotary element of the machine, and latch

means for holding said movable contact in retracted position and automatically releasing it upon a predetermined speed being exceeded. 55

4. In a speed-limiting device for rotary machines, the combination of a stationary contact, a spring-pressed movable contact, a 60 latch mounted to rotate with the machine for holding said movable contact in retracted position, and a centrifugal lever for tripping said latch.

5. In a speed-limiting device for rotary 65 machines, the combination of a stationary contact, a spring-pressed movable contact, a latch mounted to rotate with the machine for holding said movable contact in retracted position, and a spring-pressed centrifugal lever 70 having a part extending into the path of said latch whereby the latter is tripped upon a predetermined speed being exceeded.

6. In a speed-limiting device for rotary 75 machines, the combination of a stationary contact, a spring-pressed axially-moveable plunger having a contact secured thereto, a latch mounted to rotate with the machine for engaging and holding said plunger in retracted position, a centrifugal lever having a part extended into the path of said latch, and adjustable spring means for holding said lever in its inner position.

7. In a speed-limiting device for rotary 80 machines, the combination of a stationary contact, a support therefor, a movable contact mounted to rotate with the machine, and a push-rod carried by said support and adapted to engage and return said movable contact to its retracted position. 90

8. In a speed-limiting device for rotary 85 machines, the combination of a stationary contact, means for supporting said contact in line with the rotary element, a movable contact carried by an axially-moveable spring-pressed plunger, centrifugally-controlled latch means for holding said plunger in retracted position, and a push-rod carried by 95 said supporting means for manually returning said plunger to its retracted position. 100

In witness whereof I have hereunto set my hand this 19th day of September, 1903.

FRED L. STONE.
